UNITED STATES PATENT OFFICE

HENRI FRANCOIS NIOGRET, OF LYON, FRANCE, ASSIGNOR, BY MESNE ASSIGNMENTS, TO DU PONT RAYON COMPANY, OF NEW YORK, N. Y., A CORPORATION OF DELAWARE

APPARATUS FOR THE MANUFACTURE OF ARTIFICIAL SILK

Application filed April 14, 1928, Serial No. 270,104, and in France April 14, 1927.

This invention relates to the manufacture of artificial silk and more particularly to an apparatus for dry spinning cellulose derivatives. It is especially adapted to the spinning of a solution of cellulose acetate.

Considerable advantages have been obtained in the dry spinning of cellulose derivatives by carrying out the evaporation of the solvent or solvents, not in an atmosphere containing but a small proportion of vapors of the solvent or solvents but on the contrary in an atmosphere richly laden with these vapors.

Also, it has been observed that the cross-section of the filaments is affected by causing the proportion of solvents in the evaporating atmosphere to vary, and in order to do this it has been proposed to use a method consisting in arranging a closed circuit for the evaporating atmosphere with direct condensation of the evaporated solvents and to fix the concentration of solvent vapors of the atmosphere in the cell by the selection of the temperature of condensation.

This method implied, therefore, an exit of the atmosphere at a certain point of the cell and at another point of the cell a readmittance of the same atmosphere partly freed from solvents in a desired proportion.

I have now found that it is possible to dispense with an external circuit for the evaporating atmosphere and according to the present invention I perform the evaporation in an atmosphere richly laden with solvent vapors and obtain by a single large opening a gaseous exchange between the atmosphere of a heated cell where spinning is in process and the atmosphere of a cooled condenser where the solvents condense, this condenser being directly connected to the cell by the said aperture.

The atmosphere in the condenser is a mixture of air and of solvent vapor, the composition of which is determined by the temperature of condensation. The atmosphere of the cell also is a mixture of air and of solvent vapor, the content of solvents being somewhat higher than that of the atmosphere of the condenser. The difference between these two contents depends upon the

conditions under which the convection currents take place between these two enclosures, that is, upon the dimensions respectively of the cell and of the condenser, upon the quantity of solvent evaporated in the unit time, and upon the difference of temperature between the cell and the condenser, etc.

The large communication aperture between the cell and the condenser may be placed either in the vicinity of the dies, that is, where the evaporation of the solvents is most intense, or in other points of the cell, for example, at the end of the cell opposed to the dies. Several openings communicating with as many independent condensers as there are such openings may also be provided.

The filaments issue from the cell by an extremely small orifice, so that there is no appreciable loss of solvent vapors by this orifice.

It has been ascertained that from 99% to 100% of the solvents contained in the colloidion to be spun can be recovered in these conditions, this recovery being effected in an extremely economical manner by direct condensation.

I describe hereafter, as an example which is not limitative, an apparatus working in accordance with the present invention.

This description is specific to an apparatus constituting a spinning unit, but it is evident that the spinning shed or metier may comprise any number of such unit apparatus.

In the accompanying drawings, Figure 1 is a vertical section of a unit apparatus having one condenser.

Figure 2 is a vertical section of a unit apparatus having a plurality of condensers.

Referring now to the drawings wherein like reference numerals designate like parts, the reference numeral 1 designates a vertical tube (of from 6 to 10 centimeters in internal diameter, for example) provided at its upper portion with a die 2 through which the solution to be spun is extruded by any of the usual or known means. This vertical tube is heated by an external jacket 3.

A large aperture 4 causes the cell to communicate with the condenser 5, said con-

denser being cooled by an external circulation of water or by any other means and provided with an outlet pipe terminating in a receiver 6 wherein the condensed solvent is collected. From the receiver 6 the condensed solvent may be caused to pass into the collector 7, the passage thereof being controlled by a valve 10.

At the lower portion of the cell is the opening 8 for the exit of the filaments. It is so disposed that there is practically no gaseous exchange with the atmosphere outside the cell. In this manner the working of the whole cell and condenser, is that of a practically closed space.

In Figure 2 there is illustrated an apparatus having two condensers, one disposed in the center of the cell and the other in the lower portion thereof, said condensers being identical in structure to that described above and illustrated in Figure 1. It is to be understood that this figure (2) merely illustrates one modification wherein a plurality of condensers is utilized and that other positionings and/or number of condensers are possible and practical.

Under these conditions during normal spinning I have ascertained that, when spinning a solution of cellulose acetate in acetone with a condenser maintained at a temperature of about 25° C., the cell being heated at a temperature of 80° C., 99% to 100% of the solvent contained in the solution to be spun is collected in the condenser 5 and recovered.

The atmosphere of the condenser comprises a mixture of air and acetone containing 700 grams per meter cube which corresponds to saturation at the temperature of 25° C.

The atmosphere of the cell comprises a mixture of air and acetone varying between 700 grams and 1,000 grams per meter cube. The thread issues from the cell substantially dry.

At the instant of starting and during a short interval of time the apparatus is exhausted so as to free it from the excess of air it contains with respect to the quantity of air which must finally remain in the system. This exhaustion takes place, for instance, by means of a neck 9 which may be if desired connected to a recovery installation which will be naturally of very small capacity.

In this example it has been stated that the condenser is cooled by a circulation of outside water or by any other means. Satisfactory cooling may be obtained by utilizing the atmospheric air of the spinning room. When this latter method is employed, it is desirable that the condenser be of such shape or form and/or provided with other means to augment its cooling surface such as, for example, fins or small wings.

Having now particularly described and ascertained the nature of my said invention

and in what manner the same is to be performed, I declare that what I claim is:

1. An apparatus for the manufacture of artificial filaments by dry spinning of solutions of cellulose derivatives in volatile solvents comprising a closed cell, means for heating said cell, a condenser directly connected to the cell by a single large aperture, and means for cooling said condenser.

2. An apparatus for the manufacture of artificial filaments by dry spinning of solutions of cellulose derivatives in volatile solvents comprising a closed cell, means for heating said cell, a plurality of condensers each condenser being directly connected to the cell by a single large aperture, and means for cooling said condensers.

In testimony whereof, I have affixed my signature to this specification.

HENRI FRANÇOIS NIOGRET.
